Patented Nov. 12, 1912

UNITED STATES PATENT OFFICE.

JOHN T. HOPE, OF KANSAS CITY, MISSOURI, ASSIGNOR TO JOHN FRANCIS HOPE, OF KANSAS CITY, MISSOURI.

ROTARY BLOWER OR PUMP.

1,043,936.

Specification of Letters Patent. Patented Nov. 12, 1912.

Application filed December 19, 1910. Serial No. 598,632.

To all whom it may concern:

Be it known that I, JOHN T. HOPE, a citizen of the United States, residing at Kansas City, in the county of Jackson and State of Missouri, have invented certain new and useful Improvements in Rotary Blowers or Pumps, of which the following is a specification.

This invention relates to rotary blowers or pumps, and has for its object to produce means for producing a blast of air or for pumping water or other liquid, which operates efficiently and economically and is of simple, strong, durable and inexpensive construction.

With this object in view the invention consists in certain novel and peculiar features of construction and organization as hereinafter described and claimed; and in order that it may be fully understood reference is to be had to the accompanying drawings, in which—

Figure 1 is a vertical section on the line I—I of Fig. 2, with certain parts in elevation. Fig. 2, is a horizontal section on the line II—II of Fig. 1. Fig. 3 is a transverse section on the line III—III of Fig. 1.

Referring first to the blower or pump, 1 indicates a cylindrical casing provided at its ends with outturned flanges 2, and at opposite points of its periphery with outwardly projecting receiving and discharging nozzles 3 and 4 respectively.

The nozzles respectively communicate with chambers 5 and 6 produced at the periphery of the casing by providing the latter with the outwardly swelled portions 7 and 8, respectively. The cylinder is provided with V-shaped openings 9 and 10, establishing communication between the interior of the cylinder and chambers 5 and 6, the openings 9 and 11 and 10 and 12 being of such form and relation as to provide V-shaped bridges 13 and 14, which respectively bridge chambers 5 and 6. The inner faces of the V-shaped bridges form a part of the inner face of the cylinder.

Adjacent to the nozzle 4, the cylinder is provided with an external enlargement 15, formed with a recess 16, communicating with the interior of the cylinder, and fit-

ting in said recess is a packing plate 17 of Babbitt metal or like material, a hard metal plate 18, fitting in the recess as a backing for the plate 17, and bearing against said hard metal plate for the purpose of advancing the same and plate 17 to compensate for wear of the latter, is a pair of bolts 19 equipped with the customary lock nuts 20.

21 are the heads of the cylinder, provided with eccentric bearing hubs 22, one of them closed at its outer end as shown in Fig. 2, and secured in said hubs are Babbitt metal or equivalent linings 23, bolts 24 extending through the hubs and flanges 2 and securing the former firmly in place.

25 is a key securing rigidly upon shaft 26 fitted in journals 23, a rotary piston, consisting of a body and pivoted wings. The body is square in outline and its faces fit with substantially air tight joints against the inner faces of the heads 21. At each corner the square body is provided with a hook 28, projecting in the direction in which the piston is adapted to rotate, and the outer edges of the hooks for almost their full length are curved on lines struck from the center of the shaft, so that each of said curved peripheries of the hooks, once in each revolution of the piston shall engage the packing plate 17 with an air-tight relation.

29 indicates the wings, flat at their inner sides and curved at their outer sides and of such proportion that their outer surfaces shall, when the wings are closed, constitute a continuation of the curved lines described by the curved outer surfaces of the hooks. It will thus be understood that when all of the hooks are closed, the piston forms a perfect circle arranged eccentrically with relation to the cylindrical casing.

The wings are provided at their rear ends with cylindrical portions 30 constituting pivot pins snugly engaged by the hooks and are formed with curved recesses 31 receiving the free ends or terminals of said hooks.

Assuming that the blower or pump is to be driven in the direction indicated by the arrow, it will be seen that the wings begin to move outward by centrifugal force as they successively pass the packing plate 17, which is nearer the axis of motion than any other point in the periphery of the cylinder, and that they continue to open until they reach a point diametrically opposite the plate, after which they are gradually reclosed, the

engagement with the inner side of the cylindrical casing regulating and controlling the position of the blades. As the blades sweep over the bridge 13, they produce a 5 suction in nozzle 3, for any desired purpose, though in practice the blower is used chiefly as a part of a vacuum cleaning system, and receives the air after the dirt has been washed from the same by passing it 10 through the water of a tank or otherwise; the air sucked into the blower being discharged through the openings 10 and 12, chamber 6 and nozzle 4, the bridge 14, covering chamber 6, effecting the closure of the 15 wings without interfering with the discharge of the air into chamber 6 and thence through nozzle 4.

It will be apparent that the provision of 20 bridges over openings 5 and 6 is necessary for the proper operation of the blower, and the V-shaped bridge extending for the full 25 length of the chamber bridged is particularly desirable as it provides a wearing surface upon which each wing will bear during its progress over the corresponding chamber. Because of this the wear on the wings is uniform, and it will be unnecessary to remove them from time to time for regrinding.

30 In actual practice the wings open and close noiselessly and this is due principally to the fact that the air interposed between each wing and the corresponding flat side of the body constitutes a cushion, though it has 35 been found in practice that the lubricating oil with which the cylinder is kept charged, accumulates on the adjacent faces of the body and the wings in such a manner that it forms an effective sound deadener for the 40 closing movements of the wings.

In a twelve inch blower, the actual line of contact between the circumferential wall of the cylinder and the periphery of the body of the piston will approximate one-sixty- 45 fourth of an inch though to the eye the line of contact is very much in excess of the width mentioned. To produce a blower therefore which embraces as essential elements a cylinder and a circular piston, it 50 has always been desirable that the latter shall have no peripheral groove or recess which is as wide as the line of contact heretofore mentioned otherwise the air can bypass from the receiving nozzle to the dis- 55 charging nozzle and as a result air and power is not only wasted but the blower operates less efficiently than it should because it discharges the air with a pulsating instead of a continuous action. In my construc- 60 tion it will be understood that the provision of the body portion with inturned hooks and the wings with recesses into which said hooks fit snugly provides no peripheral recesses or grooves of the character men- 65 tioned, that is to say, the recesses or grooves

are represented by thin lines or joints of less width than the line of contact between the body of the piston and the circumferential portion of the cylinder. Because of this air cannot by-pass in a direction opposite to the rotation of the piston, from the receiving nozzle to the discharging nozzle each time one of the peripheral joints between a wing and hook coincides with the point of the circumferential portion of the cylinder nearest the axis of the piston, whereas with all other blowers of the general type under consideration which have come under my observation, there is a by-pass action under the conditions named.

In practice each blower is equipped with an oil reservoir 32, a valve-controlled pipe 33 leading from the lower part of the reservoir to chamber 5 of the blower. The upper end of the reservoir is provided with 85 an opening 34 communicating with the discharge nozzle of the blower and depending from the upper part of the blower is a partition 35, so as to form an inclosed chamber 36 communicating with the lower part of 90 the reservoir, and a surrounding chamber 37, which communicates with opening 34, chamber 37 being partitioned from the lower part of the reservoir by horizontal partition 38 connecting the lower end of partition 35 95 with the wall of the receptacle, and said bottom is provided with an opening 39 communicating with the lower part of the reservoir, said lower part being adapted to contain oil and having a gage 40 to indicate 100 at a glance the quantity of oil. The top of the reservoir is provided with a normally closed oil feed opening 41, and an opening 42, through which the air discharged into the reservoir by the blower, escapes, to the 105 escape pipe 43, ordinarily fitted in said opening 42 and leading to a point where it is convenient to permit the air to escape into the atmosphere.

In practice, the operation of the blower 110 effects a continuous circulation of the lubricant as well as the air as will be readily understood, it being obvious that the air and lubricant is discharged into the branched passage 37, and passes thence down through opening 39 into the lower part of the reservoir where the oil stands at the desired level, the air following the course indicated by the arrows and escaping upward through the pipe 43 as will be readily understood.

115 It will be apparent of course that this blower or pump will operate as effectively with a liquid as with a fluid and may be employed for pumping water or oil as well as air.

120 From the above description it will be apparent that I have produced a pump or blower possessing the features of advantage enumerated as desirable and I wish it to be understood that I reserve the right to make 125

all changes properly falling within the spirit and scope of the appended claims.

I claim:

1. A rotary blower or pump comprising a cylindrical casing, provided with an inlet nozzle and an outlet nozzle, a rotary piston arranged eccentrically within the cylinder and consisting of a substantially rectangular body having at each corner thereof, a portion projecting in the direction in which the piston turns and terminating in an inturned hook forming in conjunction with the body a transversely extending cylindrical journal opening, the peripheral portions of the hooks being struck from the center of the body and each hook adapted once in each revolution of the latter, to engage the inner side of the circumferential portion of the cylinder with an air-tight relation at the point of the latter nearest the axis of the body, and wings having hinge portions fitting in the journal openings and curved at their outer or peripheral sides and adapted once in each revolution to be forced inwardly against the body and while in such position form at their outer sides a continuation of the peripheral surface of the adjacent forwardly projecting portions of the body; said wings at their hinged or heel ends having transverse recesses curving concentrically of the axis of the adjacent journal openings of the body and snugly receiving the inturned hooks of the latter.
2. A rotary blower or pump comprising a cylindrical casing having a receiving nozzle

and a discharge nozzle and formed in its periphery with outwardly swelled portions providing chambers communicating with said notches and with V-shaped bridges between said chamber and the chamber of the casing the inner faces of the bridges forming a part of the inner surface of the periphery of the casing and a rotary piston consisting of a substantially rectangular body and four peripheral wings therefor arranged at equal distances apart and when closed against the body constituting with the same a circular piston the same being arranged eccentrically within the casing, the body at each corner having a forwardly projecting portion terminating in an inturned hook forming in conjunction with the body a transversely extending cylindrical journal opening, the peripheral portions of the hooks being struck from the center of the body and each adapted once in each revolution of the latter to engage the inner side of the circumferential portion of the cylinder with an air-tight relation at the point of the latter nearest the axis of the body, the said wings having hinge portions fitting in said journal openings and external recesses snugly receiving the inturned hooks of the body.

In testimony whereof I affix my signature, in the presence of two witnesses.

JOHN T. HOPE.
